BOTTLE CLOSURE

Elta Simmons, New York, N. Y.

Application June 8, 1932, Serial No. 615,987

6 Claims. (Cl. 215—41)

This invention has reference to elastic caps made of rubber or other similar elastic material, adapted for closures for bottles and similar containers, which caps may in the process of pasteurization or sterilization be adapted to permit the discharge of steam or vapor rising from the liquid contents of bottles on which they are fitted. The invention is especially useful as applied to caps for nursing bottles.

10 A principal object of my invention is to provide a bottle cap having a valve in the crown thereof which is adapted to open under internal pressure exerted in a bottle on which it is positioned, close upon the pressure being released, and hold 15 the vacuum created in the bottle by the cooling of the contents thereof.

Another principal object of my invention is to provide means on the under side of the tabs on the cap for holding the ends of the tabs sufficiently away from the bottle with which the cap 20 is used to enable a person to readily grasp the same preparatory to removing the cap from the bottle.

Another principal object of the invention is to provide means in the cap adapted to register with 25 the inside mouth of the bottle on which it is used to hold the crown portion against lateral shifting.

Another principal object of the invention is to 30 provide a relatively stiff crown to resist the pull of a vacuum created in the bottle on which the cap is used.

Another principal object of the invention is to construct the bead of the cap adapted to fit 35 over the bottle opening in such manner as to insure snugness of the cap on the bottle when in place.

Another object of the invention is to provide 40 means for conveniently manipulating the cap and putting the same into place on a bottle or other container or removing the same, which means are in the form of a tab or tabs.

Another object is to provide a cap which may 45 be placed upon a bottle without the hands coming into contact with the mouth of the bottle or the inside of the cap.

Other objects will be apparent from the following description taken in conjunction with the accompanying drawing, in which

50 Figure 1 is a side view of a cap embodying my invention;

Figure 2 is an end view of the same;

Figure 3 is a vertical section taken along the line 3—3 of Figure 2;

55 Figure 4 is a horizontal cross section taken

along the line 4—4 of Figure 3 looking in the direction of the arrows; and

Figure 5 is a cross section of my cap in position on a bottle.

Referring now in detail to the drawing, in which similar characters refer to similar parts throughout, 9 represents the bowl of the cap which is preferably made of elastic material, such as rubber. At the base of the interior of the bowl is provided a bead 10 extending circumferentially thereof and providing a constricted annulus adapted to fit over the mouth of a bottle, the upper part of said bead being adapted to be engaged by the lip of the bottle. The inner circumference of this bead preferably tapers 10 so as to flare in an outward and downward direction as shown. The outer circumference of this bead forms a rounded connection with the bowl, which is desirable for sanitary purposes. A tab 11 forming part of the bead and having 20 its base coincident with substantially half of the circumference thereof extends downwardly from said bead and may exist either singly or be duplicated as shown, one on each side of the cap. Projections or knobs 20 are provided on the under 25 side of the tabs for the purpose of holding the lower ends of the tabs away from the bottle when in use to enable ready handling of the respective tabs in the act of removing the cap from the bottle. The effect of the wide base for the tab 30 is to distribute the strain of pulling the same over a large part of the bead. The sanitary method of placing the cap on the bottle is to fit one side of the bead under the lip of the bottle, hold the adjacent tab with the forefinger of one hand 35 and grasp the opposed tab with the thumb and forefinger of the other hand, the thumb being adjacent to the neck of the bottle, and turn the tab upwards thereby reversing a portion of the same with a portion of the bead and stretching 40 the tab and with it the bead away and upward from the lip of the bottle, and pulling the tab arcuately and downwardly until the bead is entirely under the lip of the bottle. It is obvious, of course, that the cap may be put on the bottle 45 in any other suitable way.

The crown of the bowl is thickened so as to stiffen the same, and in it I have provided a valve body 12, which projects in an upward direction. The valve body is provided with a valve slit 13 and a recess 14 over which recess the projecting portion of the valve body is positioned. On each side of the slit are provided ribs 18 adapted to reinforce the material ad- 55

5 jacent the valve slit 13, said ribs preferably being disposed at right angles to the valve slit. The purpose of this arrangement is to facilitate the emission of steam and vapor from the bot-
5 tle on which the cap is placed, and to close the valve upon the release of pressure of such steam or vapor, and thereafter resist a collapsing tendency of the valve into the bottle upon a vacuum being formed therein.

10 A circumferential rib 19 is provided on the outside of the bowl which acts as a grip in press-
ing the bead 10 in placed under the lip of the bottle, and another rib 21 along the edge of the tabs is provided to strengthen the tabs and add
15 to their finished appearance and also to make them easier to grasp.

In operation, the cap is manually drawn over the opening of the bottle, the bead 10 thereof engaging the underside of the lip 17 of the bot-
20 tle and by reason of its angular tapered shape fits snugly against the neck and under the lip, giving the same a firm and tight joint. The tabs 11 follow the line of the shoulder of the bottle with the knobs 20 holding the ends of the tabs
25 sufficiently away from the bottle to enable a ready pickup of the respective tabs when its desired to remove the cap from the bottle.

To pasteurize or sterilize the contents of the bottle, the cap is placed in position as described
30 and the bottle and contents are heated in any well-known manner. The pressure of the ex-
panding steam or vapor rising from the liquid contents of the bottle will force apart the lips
35 of the valve body 12 and the steam or vapor generated in the bottle will be released, passing through the recess 14 and the communicating slit 13 of the valve into the open atmosphere. When the temperature in the bottle is reduced so as to relieve the valve of the inner pressure,
40 the valve again closes and the lips of the same are pressed together forming an air-tight seal for the contents of the bottle, and as the bottle cools further a vacuum is formed within it which tends to draw the crown of the cap into the
45 mouth of the bottle. To resist this tendency, the diametrical ends of the valve body rest upon the lip of the mouth of the bottle with the rib 22 positioned within the bottle mouth, thus over-
coming any tendency to collapse the crown of
50 the cap into the mouth of the bottle or laterally shift the same thereon. Furthermore, the ad-
jacent ends of the ribs 18, upon the vacuum con-
dition being formed in the bottle are drawn in-
55 timately into association with each other and form a bridge, and also resist the tendency of the vacuum to draw the crown of the cap into the mouth of the bottle.

It is, of course, obvious that some features of
60 the cap described may be embodied in the form of a nipple for a feeding bottle or adapted to other analogous uses. I do not wish to be con-
fined, therefore, to the embodiment shown, but what I desire to cover by Letters Patent is set
65 forth in the appended claims.

I claim:

1. An elastic cap, having a substantially rectangular bead at the base thereof, a tab extending downward from said bead and forming a continuation of the bead and extending at its base substantially half-way around the circumference of said bead and having a projection thereunder adapted to provide a ready finger hold for said tab when said cap is in position on a bottle. 5

10 2. An elastic cap, having a crown adapted to cover the mouth of a bottle and of sufficient thickness and rigidity to resist collapse when subjected to suction from within the bottle, said crown having a slit therethrough, a bead spaced from the crown for fitting under the lip of the bottle to retain the crown normally in contact with the bottle mouth, and a tab extending downward from said bead and extending at its base substantially half-way around the circumference 20 of said bead, and having a projection at the inside of the lower end thereof which forms a ready finger hold for said tab when said cap is in position on a bottle. 15

25 3. An elastic cap, having a bead at the interior base thereof, a rib at the outer base thereof, a tab extending downward from said bead, said tab extending at its base substantially half-way around the circumference of said bead, and a rib on said tab, said tab having a projection 30 thereunder adapted to provide a ready finger hold for said tab when said cap is in position on a bottle.

40 4. An elastic cap member for mounting upon the neck of a nursing bottle or the like, having 35 a bead at the interior base thereof adapted to fit under the lip of a bottle upon which said cap is positioned, a tab extending downwardly from said bead in such direction as to tend to lie against the neck of the bottle and a project-
ing knob on the under side of the tab near its lower end adapted to space the lower end of said tab away from the bottle neck so as to provide a ready finger hold to enable the tab to be grasped when the cap is to be removed. 45

50 5. In an elastic cap for sealing a bottle against external pressure while permitting the escape of internal pressure therefrom, a bowl having an arched crown concentric with and shaped to rest on the mouth of a bottle and provided interiorly with a downwardly projecting circumferential rib for engaging the interior of the bottle mouth, said crown being of sufficient thickness and rigidity to resist collapse when subjected to suction from within the bottle, said crown having a slit therethrough, and an internal bead spaced from the crown for fitting under a lip of the bottle to retain the crown normally in contact with the bottle mouth. 55

60 6. The structure defined in claim 5 in which the downwardly projecting circumferential rib with which the crown is provided has a frusto-
conical outer surface for engaging the interior of the bottle mouth to support the arched crown.

ELTA SIMMONS.
